ARTHUR MONROE SHAW, OF NEW ORLEANS, LOUISIANA

SHORE PROTECTING DEVICE

Application filed September 17, 1925. Serial No. 56,862.

The invention relates to shore protecting devices and has for its object to provide a construction of sea wall of a permanent nature, which will permit the use of well established general types of construction, but which will avoid the necessity of using heavy, expensive members, such as piling or deep foundation supports and beams for transmitting stresses to such supporting members.

10 A further object is to provide a sea wall comprising a plurality of piling vertically disposed, and which piling has disposed on its upper end a channeled coping, into the channels of which the upper ends of the piles 15 extend, and in a channel of the inner side of which the lower end of an inclined bank protecting slab is rockably mounted, thereby allowing settlement of the slab in relation to the coping, but maintaining the adjacent side 20 of the slab in position.

A further object is to provide the inner side of the coping with an eye, with which a downwardly extending arm carried by the adjacent end of the slab engages for anchoring the slab 25 and coping together and maintaining the same connected upon settling of the slab.

With the above and other objects in view the invention resides in the combination and arrangement of parts as hereinafter set forth, 30 shown in the drawings, described and claimed, it being understood that changes in the precise embodiment of the invention may be made within the scope of what is claimed without departing from the spirit of the invention.

35 In the drawings:—

Figure 1 is a front elevation of a portion of a sea wall.

Figure 2 is a vertical transverse sectional 40 view of the sea wall.

Figure 3 is a sectional view taken on line 3—3 of Figure 2.

Figure 4 is a vertical transverse sectional 45 view through a modified form of sea wall, showing a right angularly disposed engagement between the slab and coping.

Figure 5 is a sectional view through a sea wall showing an arcuate shaped engagement 50 between the bank slab and the sea wall coping.

Referring to the drawings, the numeral 1 designates a plurality of sheet piling which are adapted to be driven into the ground to a depth which will protect the structure from injury by waves and currents of the sea, 55 erosion, or by undercutting incident to seepage of water. The sheet piling extend upwardly to an elevation slightly above ordinary high tide, for instance above the water level 2. Disposed on the upper ends of the piles 1 is a coping 3, which coping is also formed from a plastic material, for instance concrete and has its under side provided with a longitudinally disposed channel 4, in which the upper ends of the piles 1 are disposed, 60 therefore it will be seen that outward or inward displacement of the coping 3 on the piles 1 is prevented. The upper inner end or corner of the coping 3 is provided with a longitudinally disposed channel 5, angular 65 in cross section and into which the wedge shaped portion 6 of an upwardly sloping pavement or slab 7 extends. The slab 7 extends upwardly and landward to an elevation above extreme storm tides. The angle which 70 the slab makes in relation to the horizontal is slightly greater than the angle of natural repose of the material 8, on which it rests. Disposed behind the sheet piling 1 is a gravel pocket 9, in the bank material 8, and it will 75 be seen that the draining water from the bank material 8 will seep into the gravel pocket 9 and collect therein and will be discharged from the pocket 9 through the pipe 10 from adjacent the top of the pocket back 80 into the water 2, therefore it will be seen that the collection of water behind the seawall structure is prevented, and by providing the gravel pocket 9, sand or other material from behind the seawall will be prevented from passing through the pipe 10, 85 consequently the washing away or displacement of the material 8 which supports the slab 7 will be prevented.

Interposed between the angular extension 95 6 of the slab 7 is a semiyielding material 11, such as is known commercially as "pre-formed expansion joint material" such for instance as pitch and imbedded in the lower edge of the slab 7 and in the coping 3 are 100

the flanges 12 of an inverted U-shaped metallic strip 13, which metallic strip is preferably formed from a ductile material of a non corrosive character such for instance as copper, and which strip is also a continuous one, and by being U-shaped allows a considerable change in the angle of the slab 7 with relation to the coping 3 without resulting in a rupture of the metallic strip 13, therefore it will be seen that passage of water between the coping 3 and the slab 7 will be prevented and at the same time settlement of the slab or the coping in relation to each other will not break the joint. Disposed between the coping 3 and the slab 7 above the metallic strip 13 is a filling of pitch 14, which is brought to a fluid state by heating and is poured into the space above the metal strip 13, fully covering the strip and protecting it from wear or abrasion. The material 14 retains its semi-plastic qualities permanently so that it may become adapted to slight changes in the form of the space which it fills, resulting from a lowering of the back or landward edge of the slab 7. Extending downwardly from the slab 7 adjacent to its lower edge is an arm 15 which is imbedded in the slab and which arm terminates in a hooked end 16, which extends through a horizontally disposed eye 17 carried by the bar 18, which is imbedded in the coping 3. The arms 15, 18 and the eye 17 are formed preferably of corrosion resistant metal for instance cast iron, and are each imbedded in its respective portion of the structure. These hooks and eyes are to be placed at suitable intervals along the line of the structure, and they prevent any movement of the slab away from the coping 3, but at the same time permit a slight arcuate movement of the slab about these points as a hinging connection. It is obvious that the slab 7 may be formed from small or relatively large sections as desired, however the slab sections are provided with expansion joints 19 formed of pitch or other material and the slab sections are connected together by means of a pliable metallic strip 20 similar to the strip 13, and which strip 20 and expansion joint compensate for lateral movement which may occur in the slab sections as the result of temperature stresses and also to give the structure flexibility which will permit each section of the slab 7 to adjust itself automatically to possible variations in the amount of settlement or subsidence of the supporting earth. Disposed beneath the metallic strip 30 is a semiyieldable material 21 similar to the material 11.

Referring to Figure 4 the structure is substantially the same as that shown in Figure 2 with the exception that the coping channel 5a in the coping 3a is right angularly shaped in cross section and the interengaging arms 15 and the eye 17 eliminated otherwise the

structure is substantially the same and the same numerals apply thereto.

Referring to Figure 5 wherein a further modified form is shown the structure is the same as shown in Figure 4 with the exception that an arcuate shaped channel 5b is provided in the coping 3b.

From the above it will be seen that a sea-wall is provided and a bank slab in connection therewith which is of a permanent nature, provided with interengaging means for preventing displacement of the parts in relation to each other means is provided whereby water will be prevented from seeping through the joints of the structure, yet said joints are of a pliable nature thereby allowing settlement of the bank slab parts without breaking the joints. It will also be seen that means is provided for discharging seepage water from behind the sheet piling.

The invention having been set forth what is claimed as new and useful is:—

1. A sea wall comprising a vertically disposed wall, a coping disposed on the upper end of said wall, the upper end of said wall being disposed in a longitudinally disposed channel in the under side of the coping, an upwardly and inwardly inclined bank slab, the lower end of said bank slab being rockably disposed in a channel in the inner side of the coping and a positive rocking connection between said slab and coping to the rear of the coping.

2. A sea wall comprising a vertically disposed wall, a coping carried by said wall, an upwardly and inwardly inclined bank slab, the lower end of said bank slab being rockably connected to the coping and a positive rocking connection between said slab and coping to the rear of the coping.

3. A sea wall comprising a substantially vertically disposed wall, a coping carried by said wall, an upwardly and inwardly inclined bank slab, a rocking connection between the lower end of the bank slab and the coping, a positive rocking connection between said slab and coping to the rear of the coping, said rocking connection comprising a downwardly extending arm carried by the slab, a rearwardly extending member carried by the coping, said arm and member being rockably interengaged.

In testimony whereof I hereunto affix my signature.

ARTHUR MONROE SHAW.
